UNITED STATES PATENT OFFICE.

HARRIS T. DUNBAR, OF BUFFALO, NEW YORK.

DRAG CLAM.

Original application filed June 13, 1923, Serial No. 645,203. Divided and this application filed June 13, 1925. Serial No. 36,958.

This invention relates to a drag-clam which is more particularly designed for picking up or gathering loose material and transferring the same from one place to another, as for instance when excavating or removing soil, gravel or the like in constructing the foundations of railways, the beds of canals and similar work.

The object of this invention is the provision of improved means for automatically connecting and disconnecting the rear end of the scoop with the free end of the arm which actuates the lid at the front end of the scoop during the operation of emptying the scoop and lowering the same on the ground.

This application is a division of an application for United States patent filed by myself June 13, 1923, Serial Number 645,203.

20 In the accompanying drawings:—

Figure 1 is a vertical longitudinal section of a drag-clam embodying my invention.

Figure 2 is a rear elevation of the latch employed for holding the operating arm in 25 the position in which the scoop or bucket is in its open position.

Figure 3 is a top plan view of the drag-clam shown in Fig. 1.

Figure 4 is a longitudinal sectional elevation showing a modified form of my invention.

Figure 5 is a top plan view thereof.

Similar characters of reference indicate corresponding parts through the several 35 views.

The body of this drag-clam is constructed in the form of a scoop which comprises a horizontal bottom 1, two longitudinal side walls 2 projecting upwardly from opposite 40 longitudinal edges of the bottom, and a rear transverse wall 3^a projecting upwardly from the rear edge of the bottom and connecting the rear ends of the side walls, thereby producing a bucket or box which is open at the 45 top and also has its front end open, so as to form an inlet mouth for the scoop.

In order to strengthen the mouth of this scoop when being hauled over or into any material, a lip 4 is provided to cause the material to be separated from the mass and directed into the scoop, the front edges of the bottom and side walls of this lip 4 are constructed in the forms of a blade or cutter so as to enable the same to enter the material 55 easily. After the scoop or bucket has been

hauled into the material sufficiently to gather a load within and ahead the front end or mouth of the scoop is closed by a hollow lid which in its closing movement gathers an amount of the material ahead and pushes 60 some of the same into the scoop. The lid and the bucket both carry material. This lid preferably comprises two vertically-swinging cheeks or side pieces 5 which are pivotally mounted on the scoop by means of 65 a horizontal transverse rod or shaft 6 passing transversely through corresponding openings or bearings in the upper front parts of the scoop side and the rear ends of said side pieces, and a transverse plate or shutter 7^a connecting the front ends of the side 70 pieces 5 and provided at its lower edge with a transverse strengthening lip or bar 8. While the scoop is resting on the material and the lid is turned upwardly into its open 75 position, the drag-clam is drawn or hauled forwardly by a drag or pull line, 9^a, connected with the lid and extending to a drum forming part of the dredging apparatus with which this drag-clam is associated. 80

Secured to the lid and projecting rearwardly from the pivot thereof is an operating arm 10^a which preferably comprises two rearwardly converging side bars which are secured at their separated inner or front 85 ends to the side pieces of the lid while their rear ends are connected with each other in any suitable manner.

Means are provided for automatically locking the lid in its open position after the 90 drag-clam has been shifted into a position in which the load is discharged therefrom.

In the construction shown in Figs. 1, 2 and 3 automatic locking means are provided which comprise a locking latch 36^a which is 95 pivotally mounted on a head 32^a at the rear or outer end of the operating arm 10^a and has a downwardly projecting loop 36^b adapted to engage with a hook 34^a on the rear wall 3^a of the scoop and a forwardly projecting tail 41^a adapted to engage with the lower edge 32^b of the head 32^a below the guard sheave 29^a which forms a stop for the same. The drag or pull line 9^a connects with the outer lower corners of the lid or shutter 7^a and the dump line 31^a connects at its rear end with an eye 31^b on the inner rear corner of the scoop and passes around a sheave 15^a mounted on linkage 22^a which forms part of the hoisting fall and which is 100 105 110

attached at its lower end to the free end of the operating arm and carries at its upper end a sheave 26^a around which the hoisting line or fall 23^a passes. The dump line 31^a at times also passes around the sheave 29^a. In this construction, the arm 10^a rests on a stop 33^a formed by upper edge or the rear wall 3^a of the scoop while the hoisting fall 23^a is slackened and the scoop is being 10 dragged forwardly by the pull line 9^a and the latch 36^a is disconnected as shown in Fig. 1. Later as the scoop is turned by the dump line 31^a into its opened position with its rear wall 3^a uppermost, the operating arm 10^a approaches the rear wall of the scoop, the locking latch loop 36^b, being held in proper position by the tail 41^a against the stop 32^b, will pass beyond hook 34^a and engage with the same when the drag-clam returns to the position in which its rear wall 3^a is uppermost and the lid has been swung into an open position. Thereafter, slackening of the hoisting fall 23^a as shown in Fig. 1 will again permit the locking latch loop 36^b to 25 swing by gravity away from the locking hook 34^a to permit subsequent closing of the lid by an upward pull of the hoisting fall 23^a when sufficient material has been gathered into the scoop during its forward movement by the pull line 9^a.

The construction and operation of the drag-clam shown in Figs. 4 and 5 is substantially the same as that shown in Figs.

1 and 3 with the exception that in Figs. 4 and 5 the sheave 15^c which receives the dumping line 31^b and the sheave 26^b which receives the hoisting line 23^b are both mounted in a special integral casing 21^b which is connected by a linkage 22^b with the free end of the operating arm 10^a.

As the operating arm is lifted by the hoisting line 23^a the lid is closed to confine the load in the scoop and at this time the dump line 31^b engages the guard sheave 29^a on the operating arm so that no interference occurs.

I claim as my invention:

A drag-clam comprising a scoop having an inlet at its front end and an upright wall at its rear end said wall being provided at its upper edge with a stop face, a vertically swinging lid pivoted on the scoop and adapted to control the inlet of the same, an operating arm projecting rearwardly from said lid and provided with a stop face adapted to engage the stop face of said rear wall, a hook arranged on the rear side of said wall and having a downwardly facing mouth, and a locking latch having a bifurcated hub straddling said arm and pivoted thereto, a loop depending from said hub and adapted to engage said hook and a tail projecting forwardly from said hub and adapted to engage said stop face on this wall.

HARRIS T. DUNBAR.
